Attorney, Agent, or Firm—Porter, Wright, Morris & Arthur

[57] CLAIM

The ornamental design for a desk, as shown and described.

DESCRIPTION

FIG. 1 is a perspective view of the desk showing our new design;

FIG. 2 is a right side view thereof;

FIG. 3 is a left side view thereof;

FIG. 4 is a front view thereof;

FIG. 5 is a top view thereof;

FIG. 6 is a rear view thereof;

FIG. 7 is a bottom view thereof; and,

FIG. 8 is a right side view of a modified form of the desk shown in FIG. 1, the left side being a mirror image thereof; the front, top and rear of the desk being the same as that shown in FIGS. 4-6 without the foot rest.
